UNITED STATES PATENT OFFICE.

PAUL KÖTTGEN, OF BERG-GLADBACH, NEAR COLOGNE, PRUSSIA, GERMANY.

BOTTLE-STOPPER.

SPECIFICATION forming part of Letters Patent No. 389,707, dated September 18, 1888.

Application filed July 26, 1888. Serial No. 281,134. (No model.)

To all whom it may concern:

Be it known that I, PAUL KÖTTGEN, a subject of the Emperor of Germany, and a resident of Berg-Gladbach, near Cologne, Prussia, Germany, have invented certain new and useful Improvements in Bottle-Stoppers, of which the following is a specification.

My invention relates to air-tight bottle-stoppers in which the stopper is held tight in the neck of the bottle by projections on the same, which fit into a bayonet-joint in a band which is fitted round the neck of the bottle.

In order to make my invention more clear I refer to the accompanying drawings, which form part of this present application, and in which similar letters denote similar parts throughout the different figures.

Figure 1 is a front view of my improved bottle-stopper fitted to a bottle when open. Fig. 2 is a side view of the same open. Fig. 3 is a side view of the same shut. Fig. 4 is a side view of the same when pressed air-tight in the neck of the bottle by the action of the bayonet joint.

The stopper consists of a bow, *a a*, which has a flat plate, *A*, on the top, to which is secured an elastic washer, *f*, which may be made from india-rubber, cork, or other suitable substance riveted or screwed to the plate *A*. The bow *a* is provided with pins *b b* on the lower ends of the arms, which are guided in the slots *S S* in the neck of the bottle. Under the head *c* of the bottle is a ring, *h*, which can revolve round the neck of the bottle, the ring *h* being provided with two diagonal slits, *i i*, and the vertical slits *g g*. The ring *h* can be formed out of two halves, screwed or otherwise fastened together, or can be made from one piece.

The fastening of the stopper in the bottle is

as follows: The bow *a a* is pressed down, as shown in Fig. 3, the pins *b b* being led into the slits *g g* of the ring *h*, while the washer *f* comes over the mouth of the bottle. The ring *h* is then turned from the right to the left in the direction of the arrow, Figs. 3, 4, and the pins *b b*, being guided in the slits *i i*, are forced down on account of the wedge or screw shape of the said slits *i i*, and so is the plate *A*, and the washer *f* forced tight down on the mouth of the bottle, as seen in Fig. 4.

To open the bottle, all that is necessary is to turn the ring *h* in the contrary direction, and when the slits *g g* come opposite the pins *b b* the bow *a a* and plate *A*, with the washer *f*, can be lifted up, as seen in Fig. 2, and the same turned over to the side in the direction of the arrow, Fig. 2.

The bow *a*, plate *A*, and washer *f* are held to the neck of the bottle by the pins *b b* in the slots *S S*, and so prevented from falling off the bottle and being lost.

Having now fully described my invention, what I desire to claim and secure by Letters Patent of the United States, is—

A bottle-fastener consisting of the hoop *a a*, having the plate *A* on top, and provided with the pins *b b* on the lower ends of the same, and washer *f*, in combination with slots *S S* in the neck of the bottle, and ring *h*, with diagonal slits *i i* and vertical slits *g g*, substantially as and for the purpose described.

In witness whereof I have hereunto set my hand in presence of two witnesses.

PAUL KÖTTGEN.
